SELF-ADJUSTING WRENCH

Filed Sept. 26, 1944

UNITED STATES PATENT OFFICE

2,464,555

SELF-ADJUSTING WRENCH

Francis J. Carnelli, New York, N. Y.

Application September 26, 1944, Serial No. 555,775

1 Claim. (Cl. 81—99)

1

My invention relates to wrenches, particularly to wrenches having a handle with a fixed jaw and a slot near one end and a swinging jaw extending through the slot of said handle.

In wrenches of the above type it has heretofore been difficult and expensive to form an accurately positioned slot in a handle of substantially integral construction.

My present invention obviates this difficulty and provides a construction which enables a slotted handle to be easily and accurately constructed of great strength and rigidity and which may be easily assembled.

In my invention a wrench handle is provided near its fixed jaw with a transverse stepped recess to form a connecting shank between the handle and the jaw and of a depth sufficient to receive the extension of the swinging jaw and also a bridge plate which fits the stepped portion of the recess and, with the shank, completes a transverse slot. The bridge plate is preferably mounted at its ends on the faces of the stepped portion of the recess and with its end surfaces abutting the transverse sides of the recess. These abutting faces are at an angle to the line of thrust or reaction of the pivoted swinging jaw on the handle so that the stress of this thrust is borne between these faces. This may be accomplished by suitably positioning these faces, or a part of them, as for example by forming them reversely at an angle to the line of thrust, so that they converge in a wedge-like form toward the front of the handle or in the direction of the thrust or reaction of the swinging jaw.

A preferred embodiment of this invention is illustrated in the accompanying drawing in which

Figure 1 is a side view thereof, shown partly broken away;

Figure 2 is a plan view thereof;

Figure 3 is a view, similar to that of Figure 2, showing only the upper portion of the handle member of the device; and

Figure 4 is a perspective view of the head or upper jaw member of said device.

It will be noted that the drawing illustrates a self-adjusting wrench of the type having a pivoted upper jaw. The broad principles of the invention may be applied, however, to other types of wrenches as well.

Referring now to the drawing, the self-adjusting wrench shown comprises a handle member 10, a head member 20, a pivot 30 and a tension member 40.

The handle 10 comprises a two piece construction, each member of which may be of drop-

2

forged manufacture. The main unit consists of a handle portion 11, an off-center shank portion 12 and a jaw portion 13 which is situated above the shank thus forming a transverse recess which being open may be easily forged and machined if necessary. The secondary unit consists of a plate 14 which corresponds to the shank in shape and function. Both may be reversely curved to an extended S shape. The opposite ends of said plate lie on converging lines, 14^a and 14^b that is, on lines which converge in the direction of the back or top of the wrench, and diverge in the direction of the front or bottom thereof. The plate is set into recesses in handle 11 and jaw 13 which correspond in shape to the end portions of said plate. Screws 15 fix said plate to said handle and jaw portions.

It will be seen in Figure 2 that a slot 16 is formed between said plate and said shank when 20 the plate is affixed as aforesaid. It will also be seen that a hole 17 in the shank registers with screw-threaded hole 18 in the plate, and that pivot 30 which is simply an end-threaded screw, is fixed in said hole.

25 The head member 20 comprises a drop-forged unit which is shaped, roughly, like a question mark. It has a jaw portion 21, and a shank portion 22 which is adapted to enter slot 16. It has a hole 23 which is adapted to receive pivot 30, thus enabling the head member 20 to pivot on pivot 30 when its shank is dispersed within said slot.

30 Tension member 40, which comprises a leaf spring affixed to handle portion 11 by means of screw 41, engages the head member 20 in such manner as to urge said head member upwardly around the pivot. A small recess 24 in the back of shank 22 receives said leaf spring and holds it in place with respect to said head member irrespective of the position of the latter as it swings around the pivot.

35 In use a nut, bolthead or pipe is engaged between the fixed jaw 13 and swinging jaw 21 as indicated in broken lines in Fig. 1 and pressure is applied downwardly on the handle 11. The reaction of the swinging jaw through the pin 30 on the shank 12 and on the bridge plate 14 is, therefore, upwardly as indicated by the arrow in 40 Fig. 1. This upward reaction is received and sustained by the inclined surface 14^a and 14^b of the recess in which the bridge plate is wedged. The screws 15, or other securing means, thus serve primarily to hold the bridge plate in place when 45 not in use and are not relied upon to take any

substantial part of the stress imposed by the swinging jaw.

The above invention provides a wrench having a handle which may be easily and quickly formed by drop forging or stamping of the parts or by other automatic machine processes and enables the parts to be accurately machined or finished if desired. When assembled and in use the bridge plate locks tightly into position.

Modifications of design and construction may be incorporated into the wrench without departing from the principles of the invention.

I claim:

A wrench of the type described comprising an elongated handle having a fixed jaw at one end and a transverse stepped recess extending between front and rear sides of said handle near said fixed jaw and forming jaw step, handle step and connecting shank portions, said step portions having transverse shoulders at the ends of said recess, said shoulders being reversely inclined to a wedge shape in the transverse direction so as to converge toward the rear side of said handle, a bridge plate mounted on the stepped portions of said recess and having its ends reversely inclined to abut the inclined shoulders of said jaw and handle step portions, said plate and said

connecting shank portion forming a transverse slot extending through said handle from front to rear, a swinging jaw positioned at the rear side of said handle and having a finger portion extending through said slot, and means to pivotally secure said swinging jaw on said shank and bridge plate, said means tending to wedge said bridge plate against said shoulders, when torque is applied to said handle.
